UNITED STATES PATENT OFFICE.

DAVID N. LONG, OF WAYNESBORO, PENNSYLVANIA; MARY A. LONG
EXECUTRIX OF SAID DAVID N. LONG, DECEASED.

ROADWAY.

SPECIFICATION forming part of Letters Patent No. 779,294, dated January 3, 1905.

Application filed December 20, 1902, Serial No. 136,044.

To all whom it may concern:

Be it known that I, DAVID N. LONG, a citizen of the United States, residing at Waynesboro, in the county of Franklin and State of Pennsylvania, have invented certain new and useful Improvements in Roadways; and I do hereby declare the following to be a full, clear, and exact description of the invention, such as will enable others skilled in the art to which it

10 appertains to make and use the same.

This invention relates to roadways for wagons, automobiles, and other vehicles, and has specially in view the provision of a novel and practical construction of wheel-track designed 15 for improving country roads and city streets by providing at a minimum expense a smooth, durable, and cleanly track-surface upon which the wheels of the vehicle run.

To this end the invention contemplates a 20 construction of wheel-track embodying a construction wherein a smooth traction-surface is presented for vehicles and pedestrians along roads and streets which otherwise usually present rough and unclean surfaces for travel.

25 The essential feature of the invention involved in the novel manner of laying the individual tracks is necessarily susceptible to a variety of modifications without departing from the spirit or scope of the invention; but 30 a few of the preferred embodiments are suggested in the accompanying drawings, in which—

Figure 1 is a cross-sectional view of a highway or wheel-track embodying one form of the 35 invention. Fig. 2 is a plan view of the construction shown in Fig. 1. Fig. 3 is a cross-sectional view of the improved highway or wheel-track built upon an old road-bed. Fig. 4 is a plan view of the construction shown in Fig. 40 3. Fig. 5 is a cross-sectional view of the improved highway or wheel-track built upon an old cobble-stone pavement. Fig. 6 is a plan view of the construction shown in Fig. 5.

Fig. 1 is a cross-section of a roadway, the 45 foundation 1 being preferably a well-drained soil into which depressions may be made for the concrete base 2, into which paving-bricks 3 may be bedded while it is still soft, so their upper surfaces present a nearly true and even

surface, to form smooth and durable tracks 50 for wagon-wheels, after which the spaces around or between the bricks 3 may be filled with a grout of hardening cement. By placing the concrete 2 in depressions in the roadway a good foundation for the bricks may be 55 secured, while a minimum amount of stone is required between and outside of the tracks, a single layer or two of two or three inch crushed stone being sufficient in most cases if well bound with a tenacious clay. 60

The bricks 3 are preferably set at an angle between twenty and seventy degrees from the line of the road, about as shown in a top view in Fig. 2, so the projecting corners and recesses on the side of the wheel-tracks will enable wagon-wheels to mount thereon without tending to form ruts along the sides of said tracks. The bricks 3 should be about the same angle in both tracks to present as nearly a square surface as practicable to the wheels engaging them from the outsides when returning to the tracks from the right side after turning out for passing teams. Stones 4, or brick pieces where stones are not available, may be located in the recesses on the inner 75 sides of said tracks and project above the surface of the bricks to cause the wheels to remain more readily upon the tracks. In many cases if these projecting stones are located from four to ten feet or more apart they will 80 answer the purpose and leave the space between them more even for the horses' feet. The surfaces of the stone 4 should preferably slope toward the bricks 3. The recesses between them may be filled with crushed stone. 85 Stones 5 may also be placed in the outer recesses to prevent ruts being formed next to the bricks 3; but their tops should be even with or slope downward from the upper surfaces of the bricks 3 to enable the dirt and 90 mud to readily pass off from the wheel-tracks formed by the bricks 3. In some cases it may be preferable to have one of the stones 5 project above the bricks 3 every four to ten or more feet to cause the wagon-wheels 95 to better keep on the tracks, while the mud and the dust can work off the tracks in the spaces between them. If an occasional stone

5^a projects above and some distance outward from the outer or inner recesses at nearly right angles with the bricks 3 and beyond the next one about as shown, they will form de-
5 pressions on their sides next to the bricks 3 and oblige any wheels entering said de-
pressions to mount upon said tracks. The bricks 3 can be laid flat in a horizontal crosswise po-
10 sition or at a slight outward-sloping angle,
10 about as shown, to cause the mud and water to more readily pass off from their sides. Bricks having projections 3^a extending out-
15 ward may also be used to take the place of the stones 5 and 5^a. Some of the bricks 3 and 15 3^a may also have slanting ends to allow bricks 4^a to fit closely to them.

Fig. 3 shows a cross-section of a brick road-track built upon an old road-bed, which will answer the purpose, even if of earth, if natu-
20 rally well drained. The crosswise tread-
blocks or bricks 6 may be laid flat and slope slightly outward and should be bedded in a layer of concrete 8 before the latter has hardened, so the bricks 6 will present an even
25 and true upper surface, when the spaces sur-
rounding them may be grouted with a harden-
ing cement. The inside bricks 7 may engage or interlock into depressions made by the jog-
ging of the bricks 6, about as shown in a top
30 view of Fig. 4, and in turn present jogs on
their inner sides to engage the wagon-wheels, and thus prevent the formation of ruts along the sides thereof.

The bricks 7 and 7^a may slope about as
35 shown in Fig. 3 to carry the wheels upon the
bricks 6, and their outer edges may also be raised above the upper surface of the bricks 6, about as shown in Fig. 3, or their outer edges may preferably be practically even with
40 the bricks 6, especially for automobile use, so the tires will not be worn out thereby. Where obtainable preferably flat stones may be sub-
stituted for the bricks 7. Stones or bricks 9
45 may be placed in the jogs on the outer side of the bricks 6 and about even therewith. In some cases the stones 9 may be placed four to ten feet or more apart and project a little above the bricks 6 and 6^a, which latter may be laid without jogging to keep the wheels
50 on the bricks 6 and allow the mud to work off. The crushed stone or other ballast 8^a should be well compacted by rolling and then bound to secure them from raveling by filling the spaces between them, and especially their
55 upper layer, with a tenacious clay 8^b, which in turn may be covered with sand or a sandy loam to prevent the clay from raveling until thoroughly settled and compacted. The crushed stones 8^a may taper off to meet the
60 earth, about as shown, about three and one-half feet from the tracks, making a road about twelve feet wide and enabling two teams to readily pass each other, or it may rise from the bricks 6, about as shown in dotted lines,
65 to carry all of the water falling on the road to

the bricks 6 by the shortest possible distance. The bricks 6^a and 7^a may also be laid without jogging, as shown in Fig. 4, in which case stones or bricks 9 may be placed in jogs formed by occasionally using a shorter brick, or the 70 bricks 6^a may occasionally be jogged to receive them. The stones 9 should project above the bricks 6^a to prevent the wagon-wheels when traveling on the track from getting on the edges of the bricks 6^a and tend to wear them off or form ruts outside of them. The inside stones 10 may interlock in spaces in the bricks 7^a and project slightly above them to meet the same ends as the stones 9. Stones 10^a may also be placed at intervals on the in-
75 side of the tracks or bricks 7^a and project above them to force and keep the wheels upon the said tracks.

In Fig. 5 is shown a cross-section of a brick wagon-wheel track-road built upon an old cob-
80 ble-stone pavement 11. The lengthwise bricks 12 form the tracks and may be set on stone or cement 11^a and leveled to a true surface by forcing a straightedge down upon them before the cement 2 has hardened, after which 90 the spaces surrounding them may be filled with a hardening grout or cement. When the bricks 12 are scarce or expensive, they may be placed lengthwise and be jogged about as shown in a top view in Fig. 6, so the side 95 bricks or stones 13 and 14 may interlock there-
in at intervals of about two to ten feet or more or form a continuous surface like the bricks 14^a. Especially in the latter case the 100 bricks 13^a may slant toward the bricks 12 to 105 carry the wagon-wheels upon the bricks 12. The stones or bricks 14^a may also interlock into the bricks 12 at intervals or form a continuous surface. In the latter case they may slant slightly downward from the bricks 12 to 110 readily carry the mud off from them, while if used only at intervals at from about two to ten feet or more they may project above the bricks 12, as the mud will readily work off the tracks from between them. Length-
wise bricks 12^a, forming the tread or track for the wagon-wheels, may also be laid without jogging by jogging an occasional brick 12^b, 115 preferably from about four to ten feet apart, according to the grade of the road and its traffic, in which case side stones or bricks 13^b and 14^b may be placed in the jogs and project above the surface of the tracks to prevent the wagon-wheels from running onto the edge thereof and wearing them off and forming 120 ruts along their sides.

The crushed stone between and on the out-
sides of the tracks 12 should be leveled and
compacted, after which they may be secured from raveling by filling or binding with an 125 adhesive clay, preferably combined with water, either before or after using. The crushed stones may also be used to level any uneven-
ness in the old pavement before binding with clay. 130

- What I claim as my invention, and desire to secure by Letters Patent, is—
1. Wheel-tracks of paving-blocks set at an angle from the line of said tracks deviating 5 from a right angle.
  2. Wheel-tracks of paving-blocks set at an angle from the line of said tracks deviating from a right angle, to form projections to engage vehicle-wheels and carry them upon said 10 tracks.
  3. Wheel-tracks of paving-blocks set at an angle from the line of said tracks deviating from a right angle the projecting corners of which engage projecting stones or bricks to 15 carry wheels upon said tracks.
  4. Wheel-tracks of paving-blocks set at an angle from the line of said tracks deviating from a right angle, forming alternating recesses and projections on the sides thereof.
  5. Two tracks for wagon-wheels of bricks set at nearly the same angle in each track, said angle deviating from a right angle.
  6. Wheel-tracks of paving-blocks set at an angle from the line of said tracks deviating 20 from a right angle, recesses on the inner sides thereof engaging projections.
  7. Wheel-tracks of paving-blocks set at an angle from the line of said tracks deviating from a right angle, recesses on the inner side 25 thereof and projections from said recesses extending above the surface of said tracks.
  8. Wheel-tracks of paving-blocks set at an angle from the line of said tracks, deviating from a right angle, recesses on the inner sides 30 thereof, projections from said recesses extending beyond the line of said tracks.
  9. Wheel-tracks of paving-blocks set at an angle from the line of said tracks deviating from a right angle, recesses on the inner sides 35 thereof, projections from said recesses extending above the surface of said tracks and sloping toward said tracks.
  10. Wheel-tracks of paving-blocks set at an angle from the line of said tracks, deviating 40 from a right angle, recesses on the inner sides thereof upward projections from said recesses sloping upward from the surface of said tracks.
  11. Wheel-tracks of paving-blocks set at an angle from the line of said tracks deviating 45 from a right angle, recesses on the inner sides thereof upward projections from said recesses at wide intervals.
  12. Wheel-tracks of paving blocks or bricks set at an angle from the line of said tracks recesses on the outer sides of said tracks, substantially as set forth.
  13. Wheel-tracks of paving blocks or bricks set at angle from the line of said tracks, recesses on the outer sides of said tracks, outward 50 projections from said recesses.
  14. Wheel-tracks of paving blocks or bricks set at an angle from the line of said tracks, recesses along the sides of said tracks, outwardly extending projections from said recesses, sloping 55 downward from said tracks.
  15. Wheel-tracks of paving blocks or bricks set at an angle from the line of said tracks, recesses along the sides of said tracks, upwardly-extending projections from said recesses at intervals from about four to ten feet or more 60 to enable the mud to work off the tracks in the spaces between them.
  16. Wheel-tracks of paving blocks or bricks set at an angle from the line of said tracks and sloping from horizontal.
  17. Wheel-tracks of paving blocks or bricks set at angle from the line of said tracks, recesses on the outer sides of said tracks, said 65 bricks laid flatwise.
  18. Wheel-tracks of paving-bricks having occasional angular projections.
  19. Wagon-wheel tracks of paving blocks or bricks located crosswise said bricks lying flatwise and jogging from a straight line.
  20. Wagon-wheel tracks of paving blocks or bricks located crosswise, said bricks lying flatwise, and jogging from a straight line, inside 70 bricks interlocking into said jogs.
  21. Wagon-wheel tracks of paving blocks or bricks located crosswise, said bricks lying flatwise and jogging from a straight line, forming 75 projections upon their inner sides.
  22. Wagon-wheel tracks of paving blocks or bricks lengthwise blocks or bricks, inside of and adjacent to said tracks and sloping upward therefrom, their outer edges being nearly even with said tracks.
  23. Wagon-wheel tracks of paving blocks or bricks stones projecting outwardly and downwardly therefrom.
  24. Wagon-wheel tracks of paving blocks or bricks stones projecting upwardly on the outside therefrom at intervals of about four to ten feet or more.
  25. Wagon-wheel tracks of paving blocks or bricks blocks or bricks lengthwise of and adjacent to said tracks along the inner marginal edges thereof and upwardly-projecting stones on the outside of said tracks at intervals of four to ten feet.
  26. Wagon-wheel tracks of smooth-surfaced paving blocks or bricks jogging from a straight line and upward projections at wide intervals from said jogs.
  27. Wagon-wheel tracks of smooth-surfaced paving blocks or bricks jogging from a straight line, side bricks or stones projecting from said jogs.
  28. Wagon-wheel tracks of smooth-surfaced paving blocks or bricks jogging from a straight line, side bricks or stones projecting from said jogs in an inward direction at an upward angle from the surface of said tracks.
  29. Wagon-wheel tracks of smooth-surfaced paving blocks or bricks jogging from a straight line, side bricks or stones projecting from said jogs in an outward direction at a horizontal or downward angle from the surface of said tracks.
  30. Wagon-wheel tracks of paving blocks

or bricks jogging from a straight line, side bricks or stones projecting from and between said jogs in an inward direction at an upward angle from said tracks and forming a continuous surface.

31. Wagon-wheel tracks of paving blocks or bricks jogging from a straight line, side bricks or stones projecting from and between said jogs in an outward direction at a horizontal or downward angle from said tracks and forming a continuous surface.

32. Wagon-wheel tracks of paving blocks or bricks jogging from a straight line, side bricks or stones projecting from said jogs, in an outward and upwardly direction at intervals of about four to ten feet or more.

33. A wheelway of crosswise bricks at an angle from right angle with said way, some of said bricks having angular projections substantially as set forth.

34. Projections extending from the sides of wheel-tracks at nearly the usual angle of

wheels when mounting thereon, forming a depression between said projections and said tracks to catch and force wagon-wheels to mount thereon without sliding and forming ruts on the sides of said tracks, substantially as set forth.

35. Projections at wide intervals extending from the sides of wheel-tracks at nearly the usual angle of wheels when mounting thereon, substantially as set forth.

36. Projections at wide intervals extending from the sides of wheel-tracks at nearly the usual angle of wheels when mounting thereon, stone ballast between said projections adjacent to said tracks, substantially as set forth.

In testimony whereof I affix my signature in presence of two witnesses.

DAVID N. LONG.
